G. J. PRAT

INDUCED AND SUCTION DRAFT DEVICE

Filed June 4, 1920

Inventor:
George Jules Prat
by Knight Br.
his Atty.

UNITED STATES PATENT OFFICE.

GEORGES JULES PRAT, OF PARIS, FRANCE.

INDUCED AND SUCTION DRAFT DEVICE.

Application filed June 4, 1920. Serial No. 336,523.

To all whom it may concern:

Be it known that I, GEORGES JULES PRAT, citizen of the Republic of France, residing at Paris, France, 146 Avenue des Champs Elysees, have invented certain new and useful Improvements in Induced and Suction Draft Devices, of which the following is a specification.

The object of the invention is to enable induced draft—that is to say draft in which the fan draws only a portion of the flue gases and blows it into the chimney, said portion carrying along the remainder of the flue gases by ejector action—to be transformed into suction draft—that is to say draft in which the whole of the flue gases are passed through the fan. This is effected by providing an auxiliary fan adapted to cooperate with the main fan in such a manner that either fan is capable of operating alone for induced draft, but that the two fans will work simultaneously for suction draft, a movable means being provided to shut off in the latter case the direct passage of gases between the chimney foot and its upper portion except by way of the fans.

The accompanying drawing illustrates diagrammatically a partial vertical section 30 of a chimney provided with an arrangement in accordance with the invention, one of the fans being shown in vertical section.

At the foot of the chimney *a* which is of suitable bi-conical form, are arranged two centrifugal fans *d*, *g* whose inlets *p*, *p*¹, respectively, are open to the lower chimney portion so as to receive the combustion gases, and their blades *g* open into the stationary discharge chamber such as *r* which terminates in a delivery pipe *c* for fan *d*, and *f* for *g*. Said pipes *c*, *f* terminate in blowing nozzles *b*, *e* respectively, which open into the chimney, the nozzles *b*, *e* are preferably concentrically arranged, one inside the other. A movable shut-off device or damper *h* surrounds the outer nozzle *e*, and is adapted to be raised vertically by means of chain *i* passing over pulleys *j* and operable by a windlass *k*; all these parts are shown diagrammatically and may be replaced by any other known means for raising and lowering the damper. The fans *d*, *g* are each mounted on a shaft such as *s* and each fan

is individually driven by a suitable source of power, for instance an electro motor *t*. 55

In working with induced draft, the damper *h* is lowered around the nozzle *e* in the position shown in full lines. One of the fans *d* or *g* is alone operated, and draws in a portion only of the flue gases through 60 its inlet *p* or *p*¹ and forces it through its discharge pipe *c* (or *f*) and nozzle *b* (or *e*) back into the upper part of the chimney *a*. Said portion of gases issuing from *b* (or *e*) draws by induction the remainder of the 65 flue gases that ascend directly up the chimney as shown by arrow *F* and around the nozzles *b*, *e*.

For direct suction draft, the damper *h* is lifted to the position indicated by dotted 70 lines until it closes the space between the nozzle *e* and the wall of chimney *a*. Thereafter no gases can pass directly up the chimney, but the two fans *d*, *g* will draw the whole of the flue gases through their inlets 75 *p*, *p*¹ and force them jointly through their respective discharge pipes *c*, *f* and nozzles *b*, *e*.

The purpose of this method of operation is the following: When centrifugal fans are 80 driven at substantially constant speed, as for instance when they are driven by an asynchronous electric motor, it is well known in the art that their efficiency is high only for a given volume of gases delivered with the so-called equivalent orifice. If one fan alone were working, its efficiency, if good when it delivers the gases for induced draft, would not be satisfactory when the larger volume of gases is to be delivered 90 for suction draft. By causing a second fan of suitable capacity to deliver the remainder of the gases which the first fan cannot efficiently carry, the efficiency of both fans is maintained satisfactory. 95

What I claim is:

1. In an induced draft device for chimneys or the like, a fan adapted to work alone to draw only a portion of the gases from the foot of the chimney, a nozzle blowing said portion of gases up the chimney to carry along the remainder of gases, a second fan adapted to draw gases from the foot of the chimney and provided also with a blowing nozzle, and means for shutting off the direct passage of gases up the chimney 100
- 105

whereby the two fans are caused to draw together the whole of the chimney gases.

2. In an induced draft device, a plurality of fans each adapted to draw a portion of the gases from the foot of the chimney, said fans having concentric blowing nozzles, and means for causing the fans to draw together the whole of the chimney gases.

3. In an induced draft device, a fan adapted to work singly to draw a portion of the gases from the foot of the chimney, a nozzle on the discharge end of said fan blowing said portion of gases up the chimney to draw the remainder of gases, a second fan adapted to draw gases from the foot of the chimney and provided also with a blow-

ing nozzle concentric with the former nozzle and a damper adapted to shut off the passage of gases in the chimney around the nozzles.

4. In an induced draft device, a bi-conical chimney, two fans each adapted to draw from and return to the same chimney a portion of the gases therein when either fan works alone, said fans having concentric blowing nozzles and a damper adapted to shut off the passage of gases between the nozzles and the chimney whereby the fans are caused to draw together the whole of the gases.

In testimony whereof I affix my signature.

GEORGES JULES PRAT.
